UNITED STATES PATENT OFFICE.

CHARLES F. WILLIAMS, OF ERIE, PENNSYLVANIA.

THREAD-CUTTING MACHINE.

1,318,519.

Specification of Letters Patent.

Patented Oct. 14, 1919.

Application filed July 20, 1918. Serial No. 245,817.

To all whom it may concern

Be it known that I, CHARLES F. WILLIAMS, a citizen of the United States, residing at Erie, in the county of Erie and State 5 of Pennsylvania, have invented new and useful Improvements in Thread-Cutting Machines, of which the following is a specification.

This invention relates to thread cutting 10 machines and consists in certain improvements in the construction thereof as will be hereinafter fully described and pointed out in the claims.

More particularly the invention is designed to cut tapered threads, such as are ordinarily used on pipes. The common practice at present is to cut such threads by means of dies having cutting faces of sufficient width to cover the entire thread so 20 that by giving to such cutting faces the desired taper the tapered thread results. This manner of cutting threads involves the repeated cutting of the same surface of the pipe as the threads and it also makes it difficult to extend the thread to any great 25 length. With the present machine, the cutting face is comparatively narrow so that there as little repetition in the cuts as the thread is advanced and any length of 30 thread may be made that may be desired. In carrying out the invention in order to form the proper taper with a comparatively narrow cutting face it is necessary to expand the die as the thread advances so as 35 to provide for the taper that is usually provided in the body of the tool itself.

The invention is illustrated in the accompanying drawings as follows:

Figure 1 shows a side elevation of a 40 thread cutting machine.

Fig. 2 an end elevation, a part being broken away to better show construction.

Fig. 3 a section on the line 3—3 in Fig. 2.

Fig. 4 a section on the line 4—4 in Fig. 2.

Fig. 5 a section on the line 5—5 in Fig. 2.

1 marks the machine frame, 2 the driving spindle, or head, 3 a length of pipe being operated upon, 3^a the thread as cut on said pipe, 4 the driving gear for the spindle, 5 the feed gear, and 5^b a lever for throwing in the feed gear. These are of ordinary construction. The carriage 6 is slidingly mounted on the guide 7 on the frame. It is adapted to be moved by means of the hand 55 wheel 5^b through the ordinary mechanism (not shown) for the purpose. It is also de-

signed with a change speed mechanism controlled by the levers 5^a. It will be understood that the thread itself will accomplish the feeding action after the thread is started 60 if desired so that the entire feeding action may be accomplished by starting through the hand wheel 5^b.

A standard 6^a extends upwardly from the base of the carriage 6 and the die head 8 65 extends forwardly from the standard 6^a. The stock has the radial slots 10 in which the chasers 9 are mounted. A cam ring 11 is rotatively mounted on the head or stock 8 and is with cam surfaces 13 operating on 70 the ends of the chasers for forcing them inwardly to the work. The cam ring is also provided with the cam ribs 14 which extend into the grooves 15 in the chasers 9. The purpose of these ribs is to return, or retract, 75 the chasers. Openings 16 are provided in the ring 11 so as to permit the ready assembling of the chasers. A handle 18 is provided by means of which the cam ring may be swung to set the chasers in working 80 position and to retract them.

A releasing plate 19 is also rotatively mounted on the head 8. It has a circumferential slot 20. A screw 21 extends through the slot 20 into a cam ring 11 and a 85 clamping nut 22 with an operating handle is arranged on the screw 21 and is adapted to clamp the ring 19 with the cam ring 11 so as to compel them to move in unison when in operation.

A lug 23 extends from the standard 6^a and a stop screw 24 is arranged in this lug in the path of a pin 25 secured to the ring 19. This forms an adjustable means for locating with nicety the initial position of 95 the ring 19 and in consequence the cam ring 11.

A lug 26 is secured to the ring 19 and projects into a cam slot 27 in a cam block 27^a, the cam block being secured on a post 28 by means of screws 29^a. The cam groove 27 has a pitch, or slant, sufficient to rotate the ring 19 and with it the cam ring 11 so that the chasers are permitted to expand in accordance with the 100 taper that it is desired to give the thread. As the head advances and the lug 26 moves on the cam surface, or in the cam groove 27, the plate 11 is swung to the right as shown in Fig. 2.

In the operation of the machine so far as described the dies are set by swinging the

ring 11 by means of the handle 18 so as to bring the screw 21 to the end of the slot 20. The ring 19 will be stopped by the contact pin 25 on the screw 23. It will be understood that the lug 26 will also, when in proper adjustment, rest on the cam 27. The ring 19 is clamped with the ring 11 by means of the nut 22. The work moves forward and as the thread advances the dies are expanded through the action of the cam 27 to the taper desired. When the work has progressed to the desired position the cam nut 22 is loosened. This permits of the opening of the dies through the action of the lever 18 and ring 11 and the head may be then returned to its initial position and re-set.

It is not practical, as a rule, to set the end of the pipe to an exact position. Consequently it is desirable to have the cam post 28 moved with the head 8 up to a certain position, preferably a position in which the chasers have cut into the work just the width of a chaser and to have the post 28 retarded at this point so that with the continued advance of the head the taper of the narrow chaser will be continued. To effect this result I have provided the following mechanism: The post 28 is slidingly mounted on a guide 29 on the carriage 6 and has a bracket with a perforation 30 slidingly mounted on a rod 31. The bracket is split at 32 and provided with a screw 33 on which a clamping nut 34 is mounted. It will be readily seen that when the clamping nut 34 is operated the bracket is clamped on the rod 31 and when released the rod 31 can readily move through, or slide, in the bracket. The rod 31 is stationary and is mounted at one end on the bracket 35 secured to the frame 1. The opposite end of the rod extends through a bracket 36 mounted on the carriage 6. A stop lug 37 is mounted on the carriage 6 and is provided with a stop screw 38 by means of which the initial position of the post 28 may be nicely adjusted. A spring 39 is arranged on the rod 31 and between the post 28 and the bracket 36.

As the machine is started the clamping nut 34 is loosened. The spring 39 holds the post 28 against the stop screw 38. The parts, therefore, all advance together until the chasers have cut a thread the width of the chaser. The chasers are locked against movement axially during the initial cutting by the locking of the rings together and the action of the controlling cams. The operator then operates the clamping nut 34 clamping the post 28 to the rod 31. The carriage continues to advance. The bracket 36 advancing compresses the spring 39 and the screw 38 moves to the left of the post. At the completion of the cut and prior to the starting of the next operation the clamping nut 34 is loosened and the spring 39 moves

the post 28 to its initial position against the stop 38.

What I claim as new is:—

1. In a thread cutting machine, the combination of a head; chasers in the head; means for holding a pipe, said means and head having relative axial and rotative movement for advancing a thread and giving cutting movement; devices for moving the chasers radially in the head automatically as the cutting of the thread advances to follow the taper of the thread; mechanism locking the chasers against opening through cutting pressure prior to the action of said devices; and mechanism for varying the point in the relative travel of the head and means at which the devices begin to act. 75

2. In a thread cutting machine, the combination of a head; chasers in the head; means for holding a pipe, said means and head having relative axial and rotative movement for advancing a thread and for giving the rotary cutting movement; a cam ring on the head for actuating the chasers radially; devices for actuating said ring automatically 85 to actuate the chasers as the cutting of the thread advances; mechanism locking the chasers against opening through cutting pressure prior to the action of said devices; and mechanism for varying the point in the 90 relative travel of the head and means at which the devices begin to act.

3. In a thread cutting machine, the combination of a head; chasers in the head; means for holding a pipe, said means and head having relative axial and rotative movement for advancing the cut and giving rotary cutting movement; a cam ring on the head for actuating the chasers radially; a ring actuating cam actuating said ring to actuate 100 the chasers automatically as the cutting of the thread advances; mechanism locking the chasers against opening through cutting pressure prior to the action of said devices; and mechanism for varying the point in the 105 relative travel of the head and means at which the ring actuating cam begins to act.

4. In a thread cutting machine, the combination of an axially movable head; chasers in the head; devices automatically moving 115 the chasers in the head as the head advances; and mechanism for varying the point in the travel of the head at which said devices begin to act.

5. In a thread cutting machine, the combination of an axially movable head; chasers in the head; a ring on the head for actuating the chasers; and means for automatically actuating the ring as the head advances for expanding the chasers to follow the taper 120 of the thread. 125

6. In a thread cutting machine, the combination of an axially movable head; chasers in the head; a ring on the head for actuating the chasers; a cam device moving ini- 130

tially with the head and actuating when retarded the ring; and mechanism varying the point at which said device may be retarded.

- 5 7. In a thread cutting machine, the combination of an axially movable head; chasers in the head; devices automatically moving the chasers in the head as the head advances; means for locking the chasers 10 against radial movement prior to the action of said devices; and mechanism for varying the point in the travel of the head at which the devices begin to act.

8. In a thread cutting machine, the combination of an axially movable head; chasers in the head; a ring on the head for actuating the chasers; and a cam device moving inwardly with the head and actuating the ring when retarded, said device locking the 20 ring against movement actuating the chasers prior to the time the ring is retarded.

9. In a thread cutting machine, the combination of an axially movable head; chasers in the head; a ring on the head for actuating the chasers; a cam device yieldingly mounted to move with the head and actuating the ring when retarded; and mechanism for retarding the device.

10. In a thread cutting machine, the combination of an axially movable head; chasers in the head; a ring on the head for actuating the chasers; a cam device yieldingly mounted to move with the head and actuating the ring when retarded; and mechanism for retarding the device, said mechanism being adjustable whereby the point in the travel of the head at which the device is retarded may be varied.

11. In a thread cutting machine, the combination of an axially movable head; chasers in the head; a ring on the head for actuating the chasers; a stationary rod; a cam device slidably mounted on the rod and actuating the ring when retarded; a stop on the head initially positioning the cam device; a spring pressing the device against said stop; and means for locking the device with the rod to retard it.

12. In a thread cutting machine, the combination of an axially movable head; chasers in the head; a ring on the head for actuating the chasers; a stationary rod; a cam device slidably mounted on the rod and actuating the ring when retarded; a stop on the head initially positioning the cam device; a spring pressing the device against said stop; and a split clamp for locking the device with the rod to retard it.

13. In a thread cutting machine, the combination of an axially movable head; chasers in the head; a ring on the head for actuating the chasers; a stationary rod; a cam

device slidably mounted on the rod and actuating the ring when retarded; a stop on the head initially positioning the cam device; a bracket on the head in which the rod is slidably mounted; a spring between the bracket and the device; and means for locking the device with the rod to retard it.

14. In a thread cutting machine, the combination of a head; chasers in the head; a cam ring on the head actuating the chasers; a releasing ring on the head having a rotative movement relatively to the head and cam ring; means for locking the releasing ring with the cam ring; and a cam device acting on the releasing ring to actuate the cam ring as the cutting of a thread advances.

15. In a thread cutting machine, the combination of a head; chasers in the head; a cam ring on the head actuating the chasers; a releasing ring on the head having a rotative movement relatively to the head and cam ring; means for locking the releasing ring with the cam ring; a cam device moving initially with the head and acting when retarded on the releasing ring to actuate the cam ring as the cutting of a thread advances; and mechanism for retarding the cam device.

16. In a thread cutting machine, the combination of a head; chasers in the head; a cam ring on the head actuating the chasers; a releasing ring on the head having a rotative movement relatively to the head and cam ring; means for locking the releasing ring with the cam ring; a lug on the releasing ring; a standard; a cam on the standard engaging the lug on the releasing ring giving to the releasing ring and with it the cam ring rotative movement as the head advances relatively to the standard to expand the chasers in accordance with the taper.

17. In a thread cutting machine, the combination of a head; chasers in the head; a cam ring on the head actuating the chasers; a releasing ring on the head having a rotative movement relatively to the head and cam ring; means for locking the releasing ring with the cam ring; a lug on the releasing ring; a standard; a cam on the standard engaging the lug on the releasing ring giving to the releasing ring and with it the cam ring rotative movement as the head advances relatively to the standard to expand the chasers in accordance with the taper; and an adjustable stop fixing the initial position of the releasing ring.

In testimony whereof I have hereunto set my hand.

CHARLES F. WILLIAMS.
